UNITED STATES PATENT OFFICE.

JONATHAN MANN, OF MILTON, MASSACHUSETTS.

STONE-DRESSING MACHINE.

SPECIFICATION forming part of Letters Patent No. 320,942, dated June 30, 1885.

Application filed January 17, 1885. (No model.)

To all whom it may concern:

Be it known that I, JONATHAN MANN, of 5
Milton, county of Norfolk, State of Massachusetts, have invented an Improvement in Stone-
Dressing Machines, of which the following de-
scription, in connection with the accompanying
drawings, is a specification, like letters on
the drawings representing like parts.

My invention relates to a stone-dressing 10
machine for reducing the rough sides of a
stone as it comes from the quarry to a plane
smooth surface.

The machine comprises, in its construction, 15
a bed or carriage for supporting the stone, and
feeding or moving the same toward the cut-
ters, which act on its surface, and a number
of revolving cutter-carrying heads provided 20
with rotary sharp-edged cutting-disks, the
said cutter-heads being arranged to act upon
three sides of the stone, so that three surfaces
may be dressed or cut at the proper angle 25
with relation to one another, with but one
operation of placing the stone on the bed and
adjusting the cutter-heads with relation there-
to, substantially as hereinafter particularly set
forth and claimed.

Figure 1 is a partial front elevation of a stone- 30
dressing machine embodying this invention;
Fig. 2, a front elevation of one of the cutter-
heads, which acts upon the side of the stone;
Fig. 3, a sectional detail showing the means by
which the disk-cutter is connected with the head 35
and adjusted with relation thereto; Fig. 4, a de-
tail showing the bushing-cutter and its arm;
Fig. 5, a diagram illustrating the position of
the cutters with relation to one another, and
Fig. 6 is an elevation of one of the side cut- 40
ters.

The main frame-work *a*, and the cross-head 45
b for the head *c* for the cutters that act upon
the upper face of the stone, and the bed or
carriage *d*, movable on guides *e* by feed mech-
anism shown as consisting of a rack, *f*, pin-
ion *f'*, gearing *f''*, and pulleys *f'''*, may be of 50
any suitable or usual construction.

The cutter-heads *g* (see Fig. 2) each act upon 55
the sides of the stone, and are fastened upon
shafts *g'*, rotating in bearings *g''*, and being
longitudinally adjustable therein, a portion of
the said shaft being threaded, as shown at *g''*,
and provided with nuts *g'*, engaging the sides 60
of the bearings *g''*, and preventing longitudi-
nal movement of the said shaft after it has
once been adjusted. The said shaft *g'* has
splined upon it a gear, *g''*, meshing with a pin- 65
ion, *g''*, on the shaft *g'*, provided with an actu-
ating-pulley, *g''*, the said shaft *g'* turning in
bearings *g''*.

The cutter heads *g* are each provided with a
series of arms, *h*, (see Figs. 2 and 3,) having
sockets *h''* to receive the shanks *i* of the 70
cutter-holders *i'*, in which the shanks of the
cutters *k' k''*, &c., are free to rotate in the usual
manner. The shanks *i* are longitudinally ad-
justable in the sockets *h''*, to enable the cutters 75
k' k'', &c., to be set at a greater or less distance
from the center or axis of rotation of the cut-
ter-head, this adjustment being effected by
screws *i''* passing through ears or lugs *h'* on
the arm *h*, and provided with nuts *i''*, engag- 80
ing either side of the said lugs *h'*, the said
screws being fastened in lugs *i''*, connected with
the socket-pieces *i'* of the cutter-shanks. The
shanks *i* of the cutter-holders are also capable 85
of angular or oscillating adjustment in the
arms *h*, and are preferably adjusted by means
of wedges *m*, inserted between the said shanks
and the inner walls of the socket, as shown in
Fig. 3, thus holding the shank securely when 90
properly adjusted; but screws might be used
to effect the angular adjustment, as shown
at *m'*.

In operation the cutters are set with relation 95
to the axis of rotation of the cutter-head, so
that they move in different paths with rela-
tion to the stone, as shown in Figs. 2 and 5,
one or two of the cutters, as *k'*, being farther
from the axis of the cutter-head than the rest,
or moving in the largest circle, and the suc- 100
ceeding cutters *k'' k'''*, &c., being each slightly
nearer the axis than the preceding one of the
series. The cutter *k'* moving in the largest
circle projects least toward the surface of the
stone, which is indicated by the dotted line *S*, 105
Fig. 5, and each succeeding cutter *k'' k'''* pro-
jects slightly farther than the preceding one of
the series, so that when the stone in its feed-
ing movement arrives at the cutters, the cut-
ter *k'* moving in the largest circle will cut to
a slight depth into the surface of the stone, 110
and each succeeding cutter will act upon
the portion of the stone that has been cut
by the preceding one until the last one of the
series has cut the stone to the depth desired,

having removed all the irregularities and reduced it to a plane surface. This arrangement distributes the work equally among the different cutters, and, if desired, the said cutters may be arranged in two or more series instead of the entire number forming one series, so that the surface of the stone is acted upon in a given plane only once at each rotation of the cutter-head. In addition to the cutters k' k^2 , &c., which are intended to remove a considerable amount from the block of stone, the cutter-heads g are provided with one or more bushing or finishing cutters, n , having a series of fine cutting-edges which act upon the surface produced by the series of cutters k' k^2 , &c., pulverizing the minor projections or irregularities of the said surface, and thus leaving the said surface smooth or with a fine finish. Such finishing operation has heretofore usually been done in another machine, thus involving the expense of constructing a separate machine and requiring additional space, which objections are removed by the present invention.

The bushing-cutter is adjustable radially on its supporting-arm h^4 , (see Fig. 4,) the bearing portion of the said cutter having threaded stems n' extending through a slot, h^5 , in the said arm, and being fastened by nuts n^2 at either side of the said arm, by means of which the amount of projection of the said bushing-cutter from the cutter-head toward the stone may also be adjusted.

Either one or both of the side cutter-heads may be used independently of the cutter-head that acts on the upper-surface of the stone, and the side cutters may be mounted on frame-work independent of the main frame-work of the machine, as shown in Fig. 6, so that they may

be moved about from place to place, and set up in connection with any machine having a movable carriage for presenting the stone to the cutters.

If desired, the bushing-cutter may be set back so far as not to act on the surface of the stone, in case it is desired to leave the stone with a surface such as produced by the disk-cutters.

The duplication of the cutter-heads may be made in this machine after the manner, for example, of the machine shown in Mann and Adams' case, Serial No. 134,951, allowed April 8, 1885.

I claim—

1. In a stone-dressing machine, the combination, with a cutter-head having arms h , provided with sockets h^2 , of cutters rotatable in holders i' , having shanks i , secured in said sockets, and screws i^2 , and nuts engaging ears h' , on the arms, and lugs on the holders to adjust such holders longitudinally in the sockets, and wedges m , or their described equivalent for adjusting the holders at an angle to their sockets, substantially as and for the purpose described. 55

2. In a stone-dressing machine, the combination, with the cutter-head provided with rotary cutting-disks, of a bushing-cutter, n , adjustably secured in a slotted arm of such cutter-head by screw-bolt n' , and nuts n^2 n^2 , substantially as described. 60 70

In testimony whereof I have signed my name to this specification in the presence of two subscribing witnesses.

JONA. MANN.
